UNITED STATES PATENT OFFICE

2,457,851

DEVICE FOR USE IN CONNECTION WITH
DEFROSTING REFRIGERATORSIrving W. Taft, Weehawken Township, Hudson
County, N. J., assignor to Kidde Manufacturing
Co., Inc., a corporation of Delaware

Application October 16, 1944, Serial No. 558,829

5 Claims. (Cl. 62—1)

1

The present invention relates to refrigeration, and more particularly to a device for use in connection with defrosting refrigerators.

Mechanical refrigerators of the household type have a refrigerating unit in the upper portion of the cabinet which must be defrosted from time to time. Usually, a shallow pan is located beneath the refrigerating unit for collecting water and ice from the refrigerating unit during the defrosting thereof.

One of the difficulties encountered in defrosting refrigerators of the foregoing character is that the amount of water and ice, which eventually melts, may exceed the capacity of the pan, whereby, unless the refrigerator is attended during the defrosting thereof, the water may overflow and wet the interior of the refrigerator and the contents thereof, and then flow from the refrigerator onto the floor. Another objection is that the pan when substantially filled with water is difficult to remove from the refrigerator without spilling water therefrom. The overflowing or spilling of water from the pan makes additional work, whereby defrosting of the refrigerator becomes an unpleasant task for the housewife.

The present invention aims to overcome the foregoing difficulties and disadvantages by providing a device for use in connection with defrosting refrigerators which eliminates overflowing of the pan and makes removal of the pan while filled with water unnecessary. In accordance with the invention, this is accomplished by slowly siphoning the water from the pan and collecting the water in a receptacle which is adapted to receive all or a substantial portion of the water collected by the pan and is adapted to be readily removed from the refrigerator for emptying.

An object of the invention is to provide a simple and effective device for use in connection with defrosting refrigerators.

Another object is to provide an inexpensive and durable device for use in connection with defrosting refrigerators which is readily stored in a small space when not in use.

A further object is to provide a device for accomplishing the foregoing which is maintained in a desired position during use thereof, thereby to function with maximum efficiency.

Other and further objects of the invention will be obvious upon an understanding of the

2

illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, 10 wherein:

Figure 1 is a perspective view of a device, in accordance with the invention.

Figure 2 is a fragmentary side elevational view of the interior of a refrigerator showing the device in use.

Figure 3 is a fragmentary enlarged view illustrating the positioning of the device while in use.

Referring to Figure 1 of the drawing, there is shown a device 10 adapted for use in connection with defrosting refrigerators. The device comprises a wick member or strip 11 having any suitably shaped cross-section, for example, rectangular as shown herein, or circular, if desired. The wick member 11 is formed of woven or braided strands of fibers, or of felt or other material adapted to absorb liquid by capillary attraction and adapted to conduct the liquid from one receptacle to another receptacle at a lower level by siphon-like action. In order to obtain the best results, the wick member should be free from sizing materials or the like which may deter its liquid absorbing or transuding qualities.

In Figure 2, the device is shown as used in connection with defrosting a refrigerator. For purposes of illustration the refrigeration comprises a cabinet 15, a refrigerating unit 16 located in the upper portion of the cabinet, and a pan or shallow receptacle 17 beneath the unit 16 for collecting water and ice therefrom during defrosting 40 thereof. One end of the wick member 11 is bent over the side wall of the pan and is inserted into the liquid therein, while the other end of the wick member extends downwardly into a second receptacle 18 supported on a shelf below the pan. The

receptacle 18 may be of any suitable size and preferably is of such shape to facilitate handling thereof when filled with liquid.

In order to position and retain the wick member as shown, the wick member is provided with 50 supporting means which may be in the form of

a weight member such as a clip or ferrule 20 secured adjacent or substantially at one end of the wick member. The weight member serves to retain one end of the wick member in the bottom of the pan and prevents the wick member from falling into the lower receptacle 19 due to the weight of the wick member when it has absorbed liquid.

Additional supporting means may be provided in the form of a clip or ferrule 21 secured to the wick member adjacent to but spaced from the clip 20 which has a hook-shaped portion 22 adapted to be fitted over the lip of the pan 17 as shown in Figure 3. The hook-shaped portion 22 extends the width of the clip 21 and thereby serves as a shield to prevent liquid from dripping from the wick at the bend and flowing along the side wall of the pan.

Adjacent or at the other end of the wick member a weight member in the form of a clip or ferrule 24 is secured, which serves to maintain the depending portion of the wick member substantially perpendicular as shown in Figure 2.

The clip members 20, 21 and 24 may be formed of any suitable material, such as plastic compounds or metal having noncorrosive surfaces. Also, if desired, the clips may be removably attached to facilitate positioning them on the wick member as required and to permit attachment thereof to a new wick member.

The device also may be provided with supporting means for supporting the wick member when not in use. Such means may constitute an aperture 25 through the clip 24 and the wick member which facilitates hanging the device from a nail or the like while being stored. It will be understood that other forms of supporting means for this purpose could be utilized.

In operation, the device is arranged as illustrated and described in connection with Figures 2 and 3 of the drawing herein. The clip 20 maintains the upper end of the wick member immersed in the liquid while the clip 24 maintains the depending portion of the wick member in perpendicular position. The hook-shaped portion 22 serves to support the device on the pan and prevents accidental displacement thereof during its use.

The portion A of the wick member substantially between the clips 20 and 21 draws liquid upwardly by capillary attraction, and when this portion is soaked with liquid the liquid transudes through the depending portion B of the wick member and drips into the receptacle 19. In this manner the liquid is slowly siphoned from the pan 17 to the receptacle 19.

In order to hasten the commencement of the siphoning action, the wick member may be soaked in water prior to arranging the same in the refrigerator as shown. The siphoning action also may be accelerated by placing a small quantity of wetting agent in the pan 17.

From the foregoing description it will be seen that the present invention provides a simple and effective device for use in connection with defrosting refrigerators with a minimum amount of care and labor. The device is inexpensive to manufacture and can be sold to the ultimate user at a small cost. The device is rugged in construction and can readily withstand the usage to which it is subjected.

As various changes may be made in the form, construction and arrangement of the parts herein, without departing from the spirit and scope of the invention and without sacrificing any of its advantages, it is to be understood that all

matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

1. An article of manufacture comprising an elongated wick member, and a clip member on said wick member between the ends thereof having a portion extending about said wick member for securing said clip member to said wick member and having a U-shaped portion of greater width than said wick member adapted to be positioned over the side wall of a receptacle and serving as a support for a bent portion of said wick member extending over the same and serving as a shield to prevent liquid dripping from said wick member at the bent portion thereof.

2. An article of manufacture comprising an elongated wick member rectangular in cross-section and having a greater width than thickness, and a clip member on said wick member between the ends thereof having a portion formed with a rectangular aperture for receiving said wick member and secured to said wick member and having a U-shaped portion of greater width than said wick member adapted to be positioned over the side wall of a receptacle and serving as a support for a bent portion of said wick member extending over the same and serving as a shield to prevent liquid dripping from said wick member at the bent portion thereof.

3. An article of manufacture comprising an elongated wick member, a clip member on said wick member between the ends thereof having a portion extending about said wick member for securing said clip member to said wick member and having a U-shaped portion of greater width than said wick member adapted to be positioned over the side wall of a receptacle and serving as a support for a bent portion of said wick member extending over the same and serving as a shield to prevent liquid dripping from said wick member at the bent portion thereof, and a clip member extending about and secured to said wick member adjacent one end thereof serving as weight means.

4. An article of manufacture comprising an elongated wick member, a clip member on said wick member between the ends thereof having a portion extending about said wick member for securing said clip member to said wick member and having a U-shaped portion of greater width than said wick member adapted to be positioned over the side wall of a receptacle and serving as a support for a bent portion of said wick member extending over the same and serving as a shield to prevent liquid dripping from said wick member at the bent portion thereof, and a clip member extending about and secured to said wick member adjacent each end thereof serving as weight means.

5. An article of manufacture comprising an elongated wick member, a clip member on said wick member between the ends thereof having a portion extending about said wick member for securing said clip member to said wick member and having a U-shaped portion of greater width than said wick member adapted to be positioned over the side wall of a receptacle and serving as a support for a bent portion of

said wick member extending over the same and serving as a shield to prevent liquid dripping from said wick member at the bent portion thereof, and a clip member extending about and secured to said wick member adjacent each end thereof serving as weight means, one of said clip members having an aperture extending therethrough and an aperture in said wick member in registry with the aperture in the clip member.
